UNITED STATES PATENT OFFICE.

JOHN LJUNG, OF NELSON, MINNESOTA.

NAILING-MACHINE.

SPECIFICATION forming part of Letters Patent No. 633,764, dated September 26, 1899.

Application filed April 28, 1899. Serial No. 714,806. (No model.)

To all whom it may concern:

Be it known that I, JOHN LJUNG, a citizen of the United States, residing at Nelson, in the county of Douglas and State of Minnesota, 5 have invented a new and useful Nailing-Machine, of which the following is a specification.

This invention relates to nailing-machines, the object being to provide a simple and efficient apparatus of this character which is 10 adapted to carry a large supply of nails to be furnished for use as required, thereby avoiding the necessity of placing them in the mouth or in the pockets, and the nails can be readily fed one by one with rapidity to the proper 15 point, and by a use of the machine the workman is enabled to wear gloves or mittens in cold weather, and while the machine is primarily adapted for furnishing nails to be used in fastening shingles to roofs and other structures it is apparent that it can be employed 20 with equal advantage in many different arts.

The device includes in its construction nail-supply means and a device for carrying a nail bodily from the same to a position where it 25 may be struck by a hammer, hatchet, or like implement, and the nail-supply means consists, preferably, of a trough or magazine inclined at the proper degree and a runway communicating with the chute and along 30 which the nails may be pushed by hand and a carrier which is adapted to transfer the nails bodily from the runway for use as required, and this carrier may be of any suitable construction and operated in any convenient manner. In other words, the nail 35 carrier or separator grips the individual nail and moves the same to a position isolated from the other mechanism, and thereby provides for holding the nail in a position readily accessible for hand-nailing.

With these ends in view the invention consists in the novel combination of elements and in the construction and arrangement of parts, which will be hereinafter fully described and claimed.

To enable others to understand the invention, I have illustrated the preferred embodiment thereof in the accompanying drawings, forming a part of this specification, and in 45 which—

Figure 1 is a side elevation of a nailing-machine constructed in accordance with my

invention. Fig. 2 is a plan view of the machine. Fig. 3 is a rear elevation. Fig. 4 is a detail in perspective of the delivery end of 55 the runway for the nails. Fig. 5 is a detail plan view of the magazine-chute. Fig. 6 is a detail cross-sectional view on the line 6 6 of Fig. 5. Fig. 7 is a detail in perspective of the magazine-chute. Fig. 8 is a detail in perspective of the actuating-lever for reciprocating the nail-carrier. Fig. 9 is a detail sectional view on the line 9 9 of Fig. 2, showing more plainly the arrangement of the supporting device for the magazine-chute. Fig. 10 65 is a detail sectional view on the line 10 10 of Fig. 2, showing the relative arrangement of the upper and lower guiding-springs associated with the reciprocating nail-carrier.

Like characters denote like and corresponding parts in each of the several figures of the drawings.

The nailing-machine is intended principally for furnishing nails for use in shingling, and it is transportable, preferably, and should be 75 mounted upon a truck or framing, which latter may be of any suitable construction.

The truck represented is denoted by T, and it consists of two side bars 2, joined at the front and rear by the cross-pieces 3, these 80 parts usually being made of strap-iron and the cross-pieces having upturned ends to support the axles 4 and 4' of the truck, which are provided at their ends with wheels 5, adapted to roll upon a roof or other place as the apparatus is shifted from point to point.

The nail-supplying mechanism includes in its construction an inclined magazine trough or chute 6, having a slot 7 throughout its length, through which the shanks or bodies 90 of the nails project, and provided with upturned vertical side walls 8 and closed at its upper end, as at 9. This inclined chute or trough 6 is provided with the nail-receptacle 10, disposed substantially in a horizontal position and constituting with the chute the nail-magazine and having a closed end 12, in the center of which the vertical slot 13 is formed, the upper end of the slot being widened, as at 13^a, and the hole being shaped 100 to agree with the form in longitudinal section of the nail, which is passed therethrough and is advanced toward the nail carrier or picker to be conducted by the latter to the point of

use. The nail-receptacle 10 has a longitudinal slot 14, forming a continuation or prolongation of the longitudinal slot 7 in the chute, and the vertical walls 15 rise from the bottom 5 of the nail-receptacle at opposite sides of said slot 14 and merge on curved lines into the inclined bottom of the chute and divide the nail-receptacle into two compartments or chambers. The nails pass along the slot 7 and then 10 between the vertical walls 15, their heads being supported by the upper edges of said walls, and they are successively pushed through the T-shaped slot 13 and from thence pass into a runway, from which they are taken by the 15 nail-picker.

The nail-runway, to which reference has been made, is denoted by R, and it consists of two substantially similar or duplicate side pieces or strips 16, one of which is secured to 20 the upturned ends 17 of the side bars 2, while the other of which is secured to the vertical strips or bearings 18, which in turn are secured to said upturned portions 17, and the respective parts are spread or spaced apart 25 above the upper edge of the side pieces 16, thereby to permit the free movement of the heads of the nails which rest upon the runway. The innermost vertical member 18 extends upward higher than its companion and 30 is connected to the diagonal brace 19, which in turn is fastened to the adjacent side bar 2 near the front axle 4, thereby strengthening the structure. The vertical upright 18, to which I have just referred, serves to uphold 35 the locking-standard 20, to which a connection joined to the chute 6 is united.

The inner closed end wall 12 of the nail-receptacle 10 is provided on the outer side thereof and at the opposite sides of the vertical slot 13 therein with the oppositely-arranged pairs of inclined retaining-flanges 21, forming therebetween recesses 21^a to receive the coöperating wings or flanges 22, fitted, respectively, to opposite sides of the runway R at the inner end thereof, said wings 22 being upwardly convergent, so as to register in the recesses between the retaining-flanges 21, and thereby providing a rigid detachable joint or connection between the contiguous ends of the magazine-chute and said runway, whereby the slots of the runway and of the magazine-chute will remain in precise alignment, so as to form direct continuations, and thereby permit of the free travel of the 55 nails from the magazine and upon the runway to the discharging end of the latter.

The standard 20, to which I have hereinbefore alluded, is vertically disposed for the major part of its length and terminates at its 60 lower end in the transverse extension or foot 23, provided at its end with a hook 24, adapted to engage the bail 25 near its middle, and said bail has eyes or openings 26 at its in-turned ends to receive the transverse rod 27, 65 supported by the ears 28 on the nail-receptacle 10. The lower end of the standard 20, near its transverse extension 23, fits against

the projection or cross-piece 29, which connects the parts 17 and 18, and it is bent inward and forward near its upper end to form a 70 loop 30, which partially embraces or straddles the part 18. The said standard is projected upward beyond this loop 30 and is provided with a second and substantially U-shaped bend, the upper branch 31 of which is materially longer than its companion and constitutes the head of the standard and receives the loop or eye 32 at the bend of the angular connecting-piece 33, one end of said connecting-piece being coiled to receive the stirrup 80 34, located at a convenient point in the height of the chute 6. The shorter leg of the connecting-piece 33 is provided with a hook 35, adapted to engage in an opening in the upright 18. 85

From the foregoing it will be understood that the member or part 18 constitutes a rigid upright support for the magazine-chute, and at this point it is to be observed that the loop 30 of the locking-standard 20 is sprung into 90 engagement with one edge of the supporting-upright 18, whereby the locking-standard will exert a leverage upon the cross-pin 29, with the latter as a fulcrum, and cause the engaging hook 24 to exert a strain upon the bail 25, and thus insure the rigid positioning of the lower end of the magazine-chute, while the connecting piece or wire 33 by reason of its engagement with the upper branch 31 of the locking-standard and also with the supporting-upright 18, as plainly shown in Fig. 3 of the drawings, provides for properly bracing the main inclined portion of the chute. Furthermore, the parts referred to are separably associated together, whereby the magazine-chute may be readily detached from the remainder of the machine or swung to 31. 100

To load the machine, it is properly grasped and a handful of nails are put into the nail receptacle or box 10 when the device is in its 110 normal position, after which the latter is tilted, allowing the nails to slide slowly toward the top of the trough, at which point the nails are momentarily held and slowly freed, so that they may escape in scattered 115 order and run down the trough and pass into the elongated slot 7 until the heads of said nails strike the bottom of the trough. The nails can then pass from the trough between the vertical walls 15, and to prevent their 120 jumping out the stop or arresting device 26^a is disposed in their path and is preferably carried by the upper end of the wall 12 upon the inside thereof and consists of a resilient or spring finger adapted to be struck by the 125 foremost of the nails and which permits the nails to pass between the opposing sections of the runway R, the nails being successively taken from the delivery end of the latter and bodily conveyed therefrom for use as occasion demands.

The uprights 37 are secured to the two side pieces 16 of the runway extending upward therefrom and being spread apart near said

runway sufficiently as to permit the free progress of the nail-heads, and the U-shaped bar 38 is secured to these strips and also to the outer uprights 18 and extends downward 5 and rotatively supports the axle 39, provided with the guide-wheel 40.

The nail-carrier is denoted by N, and it is reciprocated across the discharge end of the runway transversely thereof and is of such 10 a construction as to pick the nails singly from the runway and advance them to a place beyond the same, where they may be driven home by a hatchet or like implement, and as each nail is required the machine will be 15 moved forward to repeat the operation.

The nail-carrier N has two fingers 41 and 42, respectively, the working ends of which are in proximity and which are made sufficiently resilient or springy to assure them 20 obtaining a firm hold upon the nails, and said nail-carrier is provided with a slide-loop 43, which embraces and slides upon the guide-rods 44, projecting in parallelism from the outer side piece 16 of the runway, said rods 25 constituting a convenient support for the nail-carrier.

The runway has a recess or notch 45, through which the inner branch or finger 41 of the nail-carrier N reciprocates, and said branch 30 has near its end the cut-away portion 46, between which and the adjacent finger 42 the nails are singly received and conducted forward on the working stroke of the nail-picker. By cutting away the inner finger 41, as just 35 stated, a thin springy extension is provided upon the same. The nails are pushed along the runway and the foremost one will abut against the outer finger 42 when the said carrier is in its retracted position, and when the 40 carrier is moved forward the reduced end of the finger will select the foremost nail from the series and will press the same against the outer finger, so that when said carrier or picker is advanced the nail thus held will be 45 moved away from the runway. The terminal portion of the finger 42 facing the portion 46 of the finger 41 is provided with a nail-engaging notch 46^a, which assists in holding the nail between the contiguous ends of the 50 fingers until the machine has advanced.

Associated with the reciprocating nail-carrier N is a pair of upper and lower guiding-springs 65 and 66, respectively. The upper guiding-spring 65 is coiled upon one of the 55 guide-rods 44, as at 67, and has one end thereof fastened to a fixed part of the framework, as at 68, thereby leaving its other end free to exert a spring-pressure upon the nail-carrier N. The said upper guiding-spring 65 is 60 arched over the guide-support for the nail-carrier and has the free terminal thereof depend between the separate fingers or branches 41 and 42 of the carrier, and normally the pendent free end of the guiding-spring 65 65 bears against the spring stop plate or projection 69, which is projected from the outer side of one of the guide-rods 44. The lower

of said guiding-springs 66 is also coiled, as at 70, upon one of the guide-rods 44 and is secured fast at one end to a fixed part of the 70 framework, thereby leaving its other end free to exert a spring-pressure against the nail-carrier. The main arm of said lower guide-spring 66 is arched beneath the guide-supports of the nail-carrier and is normally arrested 75 against one of the guide-rods 44, as plainly shown in detail Fig. 10 of the drawings, and the free terminal of said lower guiding-spring 66 is extended beyond the contiguous guide-rod 44, against which it rests, and is 80 disposed directly beneath the nail-carrier N to prevent downward displacement thereof, while at the same time leaving the nail-carrier sufficiently loose to insure the engagement 85 thereof with a nail in a manner to be hereinafter fully explained.

With reference to the action of the upper guiding-spring 65 it will be noted that the stop plate or projection 69 keeps the spring normally out of engagement with the nail-carrier, 90 especially at the moment the carrier engages the nail and swings the same laterally and outward from the contiguous end of the runway R. When this occurs, the nail-carrier presses outwardly against the pendent free 95 end of the spring 65, and the latter will therefore move the nail-carrier back again to its normal position, so that the nail between the contiguous ends of the fingers thereof will be carried alongside of the longitudinally-disposed guard 71, arranged at one side of the truck-frame. Said longitudinally-disposed guard 71 is provided with a pendent foot portion 72 beyond the discharging end of the runway R, which foot portion constitutes a 100 nail-carrier rest, against which the gripping end of the nail-carrier is thrown as it advances to a position to carry the nail contiguous to the angular hammer-guide 73, formed in the body of the guard 71 adjacent to the 105 rest-foot 72. At this point it will be observed that the inner finger or branch 41 of the nail-carrier is provided with a deflected portion 41^a, which rides against the pendent end 110 of the spring 65 and causes the advance 115 end of the nail-carrier to be thrown alongside of the rest-foot 72, as indicated in dotted lines in Fig. 2 of the drawings. When the nail has been carried adjacent to the angular hammer-guide 73, the same can be grasped 120 and driven by the hammer without the latter interfering with any part of the machine. It is to be observed that the hammer-guide 73 provides a clearance-space for the head of the hammer in the hand of the operator and 125 permits the nail being moved by the carrier to a position isolated from all other working parts of the machine, whereby it is readily accessible for hand-nailing. In this connection it will also be noted that when the nail has 130 been advanced by the nail-carrier to this isolated position the nail may be started while held by the carrier and then after a slight advancement of the machine-truck the guide

73 will permit the hammer to clear the adjacent parts of the machine without moving the same laterally. The said longitudinally-arranged guard 71 is further provided with a 5 horizontal guide extension 74, arranged in substantial parallelism to one of the guide-rods 44 and constituting a part of the guide-support for the slide-loop 43 of the reciprocating nail-carrier.

10 Any convenient means may be employed for reciprocating the nail-carrier, but for this purpose the actuating-lever 47 is preferable, said lever being manually controlled and being disposed within easy reach of the work- 15 man.

The lever 47, like the nail picker or carrier N, is preferably made of wire bent to the proper shape, and it has at one end the transverse journal portion 48, supported for oscillation by the bracket 49, secured at one end to the frame 50, and said bracket is also formed of wire and has a series of coils to receive the journal or pivot extension 48. The lever extends beyond the fulcrum and is located beneath the longitudinal horizontal member of the frame and is provided at its end with a longitudinal loop 51 to slidably receive the projection at the end of the crank 52 on the shaft 53, which is supported by the 20 bracket 54 on the inner end of the frame 50, and said shaft is provided with a second crank-arm 55, coiled at its end to receive the projection at the end of the link 56.

The link or pitman 56, connected with one 35 arm of the crank-shaft 53, is provided at the end opposite such connection with an elongated loop 75, which loosely engages one end of the slide-loop 43 to provide for the reciprocation of the nail-carrier. The said elongated loop also embraces a contiguous end of 40 an auxiliary starting-head 76, which transfers the initial movement from the link or pitman 56 to the slide-loop 43. The said starting-head 76 is in the form of a cross-head and 45 is slidably mounted upon the rods 44 alongside of the loop 43, and at one end the said starting-head 76 is provided with a stop-arm extension 77, which is adapted to strike against the fixed abutment 78, fitted to the 50 guide-rods 44 and projected beyond one of said rods to lie in the path of movement of the said stop-arms 77. The function of the auxiliary starting-head 76 is to prevent movement being transferred to the slide-loop 43 of 55 the nail-carrier until the nail has been firmly engaged in the notch between the contiguous ends of the nail-carrier fingers. In this connection it will be observed that when the operating-lever 47 is elevated to provide for actuating the crank-shaft 53 the motion from the link or pitman 56 is first imparted to the end of the auxiliary starting-head, with which it engages. This end of the starting-head will be drawn against the contiguous end of 60 the slide-loop 43, and consequently impart a slight rocking movement to this loop, so as to throw the nail-carrier outwardly a sufficient

distance to remove the nail from the contiguous end of the runway, after which the nail-carrier advances and is returned to a normal 70 position by the pressure of the guiding-spring 65, as previously explained.

When the operating-lever 47 is lowered, the nail-carrier is drawn back to its initial position, ready to engage with and carry forward another individual nail.

As already pointed out, the operating-lever is grasped by the workman, and the supporting-frame 50 thereof constitutes a convenient handle, as well as assists in maintaining the operator in his position upon a roof, and the said operating-lever is preferably formed of stout wire bent into proper shape and having parallel separate grasp portions 57 and the lower pendent loop 58, between which the fingers can be thrust while manipulating the lever. The said operating-lever 47 is also provided with an upstanding stop-finger 59, adapted to engage beneath the upper horizontal portion of the frame 50 to 90 arrest the upward movement of the lever.

From the foregoing it is thought that the construction, operation, and many advantages of the herein-described shingle-nailing machine will be readily understood by those 95 skilled in the art without further description, and it will also be understood that various changes in the form, proportion, size, and the minor details of construction within the scope of the appended claims may be resorted to without departing from the principle or sacrificing any of the advantages of this invention.

Having thus described the invention, what is claimed is—

1. In a nailing-machine, the combination with the nail-supply means, of a nail-carrier having means for moving the individual nails to a position isolated from the other mechanism and accessible for hand-nailing, substantially as set forth.

2. In a nailing-machine, the combination with the nail-supply means, of a nail-carrier having means for carrying the individual nails in suspension, to a point isolated from the other mechanism and accessible for hand-nailing, substantially as set forth.

3. In a nailing-machine, the combination with a nail-supply means, of a reciprocatory nail-carrier arranged to work beyond one side of the machine and having means for moving the individual nails to a point isolated from all other mechanism so as to be accessible for hand-nailing, substantially as set forth.

4. In a nailing-machine, the combination with a nail-supply means including a runway, and a reciprocatory nail-carrier, working beyond one side of the machine and transversely across one end of the runway, said carrier having means for gripping a nail and moving it to a point isolated from all other mechanism and accessible for hand-nailing, substantially as set forth.

5. In a nailing-machine, the combination with a nail-supply means, including a runway arranged transversely of the machine-frame, and having a recessed end, a reciprocatory nail-carrier having a nail-grip movable through the recess in the runway, said nail-carrier having a play beyond the machine-frame and provided with means for carrying the nail to a position isolated from the other mechanism and accessible for hand-nailing, substantially as set forth. 75
6. In a nailing-machine, the combination with a nail-supply means, including an inclined runway, arranged transversely of the machine-frame, a reciprocatory nail-carrier arranged beyond one side of the machine-frame and movable in a plane transversely of the runway, said nail-carrier having means for gripping an individual nail and moving it to an isolated position beyond the other mechanism, and hand-operated mechanism supported on the machine-frame and having an operative connection with the nail-carrier, substantially as set forth. 80
- 15 7. In a nailing-machine, the combination of a wheeled truck-frame, a runway, a nail-supply means, a nail-carrier having means for gripping individual nails and moving the same to an isolated point from the other mechanism and accessible for hand-nailing, a hand-grasp attached to the truck-frame, and a lever coöperating with said grasp and having an operative connection with the nail-carrier, substantially as set forth. 85
- 25 8. In a nailing-machine, the combination with a portable frame having a laterally-offset guide, a nail-carrier slidably supported by said guide and having means for gripping an individual nail and moving the same to a position isolated from the other mechanism, and means, carried by the truck-frame, for imparting motion to the nail-carrier, substantially as set forth. 90
- 35 9. In a nailing-machine, the combination of a portable frame having a hand-grasp and a reciprocatory nail-carrier, movable in a direction longitudinally of the frame and beyond one side of the same, said nail-carrier having a nail-grip and movable to a position isolated from the other mechanism and entirely outside of the plane of the portable frame, substantially as set forth. 95
- 45 10. In a nailing-machine, the combination with a portable frame, a fixed guide offset from one side of the frame and arranged in substantial parallelism thereto, a reciprocatory nail-carrier slidably supported by the guide and arranged to work beyond and at one side of the latter, said nail-carrier having means for gripping the nail and advancing it to a position isolated from the other mechanism, and means, carried by the portable frame for imparting motion to the nail-carrier, substantially as set forth. 100
- 55 11. In a nailing-machine, the combination with a portable frame, parallel guide-rods offset from one side of the portable frame and arranged in parallel relation thereto, a reciprocatory nail-carrier working outside of the plane of the guide-rods and provided at one end with an approximately right-angularly-disposed loop slidably embracing said rods, said nail-carrier having a nail-grip adapted to advance the nail to a position beyond the other mechanism, substantially as set forth. 105
- 65 12. In a nailing-machine, the combination with the frame, and a nail-supply means, of a nail-carrier for the individual nails supported outside of the machine-frame, and provided with a pair of resilient nail-picking fingers adapted to exert a gripping action upon the nail, and means for causing the carrier to advance the nail to a position isolated from the other mechanism and accessible for hand-nailing, substantially as set forth. 110
13. In a machine of the class described, the combination with a nail-supply means, of the nail-carrier for the individual nails, essentially comprising a pair of nail-picking fingers, said fingers having a nail-grip for engaging the head end of the nail and holding it in a suspended position, substantially as set forth. 115
14. In a machine of the class specified, the combination of nail-supply means including a runway consisting of two substantially similar side pieces recessed at their delivery ends, a nail-carrying device movable through the recess and including a pair of picking-fingers sprung toward each other to provide a resilient nail-grip, and means for operating said nail-carrying device, substantially as described. 120
15. In a nailing-machine of the class described, the combination with a portable frame having a transversely-disposed runway, a magazine-chute detachably supported at one side of the frame and having its nail-passage in alinement with the runway, a reciprocatory nail-carrier, working transversely across the opposite end of the runway and having means for gripping a nail and moving it to a position isolated from the other mechanism, substantially as set forth. 125
16. In a nailing-machine of the class described, the combination with a truck-frame having at one side thereof an upright support, an inclined runway arranged transversely of the frame a longitudinal magazine-chute communicating at one end with the runway, fastening means detachably connecting the magazine-chute with the upright support, and a nail-carrier arranged for reciprocation across the opposite end of the runway, substantially as set forth. 130
17. In a nailing-machine of the class described, the combination with a wheeled truck-frame having at one side thereof an upright support, an inclined runway arranged transversely of the truck-frame, a longitudinally-slotted inclined chute, detachably fitting over one end of the runway and having its nail-conducting slot in communication therewith, and a locking-standard suitably engaged with

the magazine-chute and sprung into engagement with said upright support, substantially as set forth.

18. In a machine of the class specified, the combination of nail-supply means including a runway consisting of two substantially similar side pieces between which the nails are adapted to travel, and a longitudinally-slotted inclined chute adapted to transfer nails to the runway, a nail-carrying device, a truck, a standard on the truck provided at its opposite ends with transverse extensions, a stirrup on the chute a connecting-piece between the stirrup and the upper end of the standard, and a bail secured to the chute and connected to the lower end of the standard, substantially as described.

19. In a machine of the class specified, the combination of nail-supply means including a runway consisting of two substantially similar side pieces between which the nails are adapted to travel, and a longitudinally-slotted inclined chute adapted to transfer nails to the runway, a nail-carrying device, a truck, a standard on the truck provided at its opposite ends with transverse extensions, a stirrup on the chute, a connecting-piece between the stirrup and the upper end of the standard, a bail secured to the chute and connected to the lower end of the standard, projections or wings at the discharge end of the chute, and coöperating projections at the adjacent end of the runway adapted to fit between said first-mentioned projections, substantially as described.

20. In a nailing-machine of the class described, the combination with a portable frame, an inclined runway arranged transversely of the frame and provided at the upper end thereof with offstanding wings or flanges, a magazine-chute alined with the runway and having at one end flanges receiving therebetween those of the runway, fastening means detachably connecting the chute with the portable frame, and a nail-carrier arranged for reciprocation across the opposite end of the runway, substantially as set forth.

21. In a nailing-machine, the frame having at one side thereof a longitudinally-disposed guard provided with a hammer-guide constructed to leave a clearance-space isolated from the working parts of the machine, a runway for the nails, nail-supplying means, and a reciprocatory nail-carrier coöperating with the runway and arranged to work at one side of said guard, said carrier having its nail-engaging portion movable to a position in proximity to the isolated clearance-space, substantially as set forth.

22. In a nailing-machine, the frame having offset from one side thereof a longitudinally-disposed guard provided with a pendent rest-foot, and contiguous to the rest-foot being provided with a hammer-guide of an angular form to leave a clearance-space isolated from the working parts of the machine, a runway for the nails, nail-supplying means, and a re-

ciprocatory nail-carrier arranged to work across the discharging end of the runway beyond one side of the frame and adapted to be moved to a position at one side of said rest-foot contiguous to the clearance-space, substantially as set forth.

23. In a nailing-machine of the class described, the frame provided with a guide-support, a runway for the nails, a nail-supplying means coöperating with the runway, a reciprocatory nail-carrier slidably supported by said guide-support and arranged to work across the discharging end of the runway, and a pair of guiding-springs for the nail-carrier, the upper of said springs having a pendent free end extending within said nail-carrier, and the lower of said springs having its free terminal arranged beneath the nail-carrier, substantially as set forth.

24. In a nailing-machine of the class described, the frame provided with a guide-support, a runway for the nails, nail-supplying means coöperating with the runway a reciprocatory nail-carrier slidably supported by the guide-support and arranged to work across the discharging end of the runway, means for reciprocating the nail-carrier and imparting thereto an initial outward movement, and springs coöperating with the nail-carrier to sustain the same in a proper relative position to the runway, substantially as set forth.

25. In a nailing-machine of the class described, the frame provided with an offstanding guide-support having a stop plate or projection, a runway for the nails arranged transversely to said support, nail-supplying means associated with the runway, a reciprocatory nail-carrier slidably supported by said guide-support and arranged to work across the discharging end of the runway, and a pair of upper and lower guiding-springs for the nail-carrier, the upper of said guiding-springs having a pendent free end normally engaging against the stop plate or projection and extending within the nail-carrier, and the lower of said springs having its free terminal arranged beneath the nail-carrier, substantially as set forth.

26. In a nailing-machine of the class described, the frame having a guide-support, a runway for the nails, nail-supplying means associated with the runway, a reciprocatory nail-carrier having a slide-loop working upon the guide-support, an auxiliary starting-head loosely mounted upon the guide-support at one side of the slide-loop, and a suitably-operated link or pitman having a loop connection with contiguous ends of said slide-loop and auxiliary starting-head, substantially as set forth.

27. In a nailing-machine of the class described, the frame having a guide-support provided at one end with an extended fixed abutment, a runway for the nails, nail-supplying means coöperating with the runway, a reciprocatory nail-carrier having a slide-

loop loosely mounted upon the guide-support, an auxiliary starting-head loosely mounted on the guide-support at one side of the slide-loop and provided at one end with an extended 5 stop-arm, and a suitably-operated link or pitman having a loop connection with contiguous ends of the slide-loop and said auxiliary starting-head, substantially as set forth.

28. In a nailing-machine of the class de-
10 scribed, the frame provided with a guide-sup-
port, a runway for the nails, a nail-supply
means, a reciprocatory nail-carrier slidably
supported by said guide-support and arranged
to work across the discharging end of the run-
15 way, said nail-carrier having an inner mem-
ber provided with a deflected portion, and a

pair of upper and lower guiding-springs for
the nail-carrier, the upper of said guiding-
springs having the pendent free end extending
within the nail-carrier and adapted to be 20
engaged by said deflected portion thereof, and
the lower of said springs having its free por-
tion arranged to bear against the under side
of the nail-carrier, substantially as set forth.

In testimony that I claim the foregoing as 25
my own I have hereto affixed my signature in
the presence of two witnesses.

JOHN LJUNG.
